RAILWAY AND TRAMWAY TRACK

Bob Sydney Davies, Horsell Rise, Woking, and
Percival Alexander Summers, Osterley, Eng-
land

Application November 7, 1933, Serial No. 697,041
In Great Britain December 6, 1933

7 Claims. (Cl. 238—283)

This invention relates to railway and tramway tracks and has for its object to provide improvements in the means for securing rails in position whereby the transmission of shocks and vibrations of audible frequencies between the permanent way and vehicle wheels is greatly lessened or prevented altogether.

According to the invention a pad or layer of shock absorbing and sound deadening material is interposed between the means employed to hold a rail in position and a sleeper or like support.

In carrying the invention into effect the shock absorbing and sound deadening element consists of a pad of sponge rubber which is disposed below the base of the rail and may be seated in or upon the sleeper or upon or below a rail clamping element carried by the sleeper. In addition, the upper surfaces of the rail flanges are also engaged by resilient pads carried by elements which serve to clamp the rail in position.

Reference will now be made to the accompanying drawings which illustrate by way of example several constructions according to the invention and in which:

25 Figure 1 is a sectional elevation and Figure 2 is a sectional plan respectively, showing applications of the invention to rail chairs of the kind employing detachable clamping dogs.

Figures 3 and 4 are sectional elevation and 30 plan respectively showing the application of the invention to chairs clamped to a steel sleeper and

Figures 5 and 6 are sectional elevation and plan respectively showing another application of the invention to a steel sleeper.

35 In the application of the invention shown in Figures 1 and 2 a rail *g* is held in position by means of detachable clamping dogs *h* which engage the upper surfaces of the rail flanges *i*. The dogs *h* are held in position by bolts *j* which also

40 serve to position the shock absorbing pad *k* disposed in a recess *l* in the chair base *m*, the said pad lying below a lower rail clamping and supporting plate *n* upon which rests the base of the rail *g*. The pad *k* also serves as a cushioning

45 means when a load is imposed on the rail and to cushion the rail when it returns to normal position. Additional shock absorbing pads *o* are disposed between the upper surfaces of the rail flanges *i* and the clamping dogs *h* which are recessed as shown on their inner surfaces to retain said pads accurately in position.

50 In Figure 2, which shows a structure similar to that shown in Figure 1, the rail and clamping elements are removed to show the pad *k* enclosed on all its edges by the walls of the chair base *m*.

The arrangements illustrated in Figures 1 and 2 may be modified as shown in Figures 3 and 4 wherein the rail clamping dogs are arranged in the same manner and are indicated by the same reference letters as in Figure 1 but the chair base *m* is eliminated in this construction and the pad *k* rests in a recess *p* formed in the upper surface of a steel sleeper *q*, the bolts *j* being replaced by bolts *r* which not only hold the clamping dogs *h* in position but pass through the pad *k* and 10 sleeper *q*. The outer ends of the clamping dogs are formed in both constructions with downwardly projecting bearing surfaces *s* which in the construction shown in Figures 3 and 4 bear directly upon the upper surface of a lower clamping member or rail retaining and supporting plate *t* which is co-extensive with the shock absorbing pad *k* and is also positioned by the bolts *r*.

In the construction shown in Figures 5 and 6, the application of the invention is shown to a 20 steel sleeper *u* which is not recessed on its upper surface. Clamping dogs *h'* of somewhat similar construction to those shown in Figures 1 and 3 are employed and the under surface of the rail rests upon a retaining plate *v* which is recessed 25 on its upper and lower surfaces to accommodate the base of the rail *g* and the pad *k* respectively. The ends of this plate are recessed as shown at *w* to engage around the fixing bolts *r'* which in this construction also pass through the clamping 30 dogs *h'* and the sleeper *u*.

Below the pad *k* is a secondary clamping or retaining plate *x* which is recessed on its upper surface to receive the base of the pad *k* and has apertures near its ends to engage around the 35 bolts *r'*, thus preventing lateral displacement of the pad *k* or of the plates which retain it from above and below.

The utilization of shock absorbing elements in the manner above described enables, in the cases 40 where pads are disposed above and below the rail flange, the rail to be given a resilient shock absorbing suspension whilst in all cases described the passage of vibrations of audible frequency is damped and a degree of silence produced in 45 the rolling stock not previously attained.

What is claimed is:

1. Means for securing railway and tramway rails in position upon a sleeper comprising a rail supporting plate having a greater dimension than the width of the base flanges of the rail and recessed to receive and position the base flanges of the rail with said plate projecting laterally beyond the edges of the base flanges, a pad of sponge rubber disposed beneath said rail support- 55

- ing plate for the entire width thereof, a pair of clamping dogs, pads of sponge rubber disposed on the under sides of said dogs to bear upon the upper surfaces of the base flanges of the rail, and 5 means operative to adjustably lock the clamping dogs against the base flanges of the rail and the base flanges of the rail against the rail supporting plate.
2. Means for securing railway and tramway 10 rails in position upon a sleeper comprising a pair of clamping dogs disposed to exert pressure upon the upper surfaces of the rail flanges and anchored to a supporting member, pads of sponge rubber carried by said dogs and disposed to bear 15 upon said flanges, a floating rail support resiliently mounted on said supporting member and having means for positioning a rail laterally thereon, said support and resilient mounting being of an area to project laterally beyond the edges of said 20 flanges and capable of downward movement under pressure, and means cooperative with the laterally projecting portions of said support to limit lateral movement thereof and of a rail supported thereon.
- 25 3. Means for securing railway and tramway rails in position upon a sleeper comprising a plurality of sponge rubber pads disposed to support the rail flange from above and below, a rail supporting plate carried by one of said pads, said 30 plate and lower pad being of an area to project laterally beyond the edges of the rail base and said plate having means for positioning a rail laterally thereon, and locking means for retaining said pads in operative position and cooperative 35 with the laterally projecting portions of said plate to position it and a rail thereon laterally.
4. Means for securing railway and tramway rails in position upon a sleeper comprising a rail supporting plate adapted to receive the base of the rail and having portions to engage against the edges of the base flanges thereof, said plate being of an area to project laterally beyond the edges of the base flanges of the rail, a pad of sponge rubber disposed beneath said plate and substantially confined against lateral distortion, a pair of adjustable clamping dogs, pads of sponge rubber disposed in the under surfaces of said dogs to bear upon the upper surfaces of the rail flanges, and bolts operative to lock said dogs in position and also cooperative with the laterally projecting portions of said plate to prevent lateral displacement thereof. 10
5. Means for securing railway and tramway rails in position upon a sleeper according to claim 1 including a chair on the sleeper having a recess in which the rail supporting plate is mounted and in which said plate has limited lateral movement. 20
6. Means for securing railway and tramway rails in position upon a sleeper according to claim 1, wherein the sleeper has a recess therein in which the rail supporting plate is mounted and in which said plate has limited lateral movement. 25
7. Means for securing railway and tramway rails in position upon a sleeper according to claim 4, wherein the rail supporting plate has recesses in the edges of its laterally projecting portions to engage said locking bolts to prevent lateral movement of said plate. 30

BOB SYDNEY DAVIES.

PERCIVAL ALEXANDER SUMMERS.
